UNITED STATES PATENT OFFICE.

HOWARD M. DUDLEY, OF PHILADELPHIA, PENNSYLVANIA.

DYEING APPARATUS.

Application filed May 13, 1922. Serial No. 560,539.

To all whom it may concern:

Be it known that I, HOWARD M. DUDLEY, a citizen of the United States, and a resident of Philadelphia, Pennsylvania, have invented 5 certain new and useful Improvements in Dyeing Apparatus, of which the following is a specification.

My invention relates to machines for dyeing goods or material in the mass; that is to say, finished goods or material which may be loosely placed in the drum containing the dyeing liquor. Such form of machines are particularly applicable for dyeing hosiery in bulk, although available for dyeing material 10 in other forms under similar conditions, and my improved machine has been specially designed for dyeing hosiery.

An important object of my invention is to provide an imperforate rotating drum, the 20 interior of which is preferably divided into a series of chambers, separated by foraminous partition elements.

A further object of my invention is to provide the outer wall of the drum, opposite 25 each of said chambers, with a movable cover or door whereby the material may be introduced into and removed from the respective chambers.

A further object of my invention is to 30 provide one of said movable covers or doors with a supplemental opening normally closed by a suitable cover hinged to the main cover, whereby samples of the goods or material under treatment may be removed from time to time for examination.

A further object of my invention is to provide means for circulating the dye liquor throughout the chambers of the rotating drum.

A further object of my invention comprises provision for introducing steam into the drum, and a still further object of my invention is to provide means whereby the drum may be rotated while the means 45 through which the dye liquor may be introduced and discharged, and those employed for introducing steam, remain at rest.

These and other features of my invention are more fully disclosed hereinafter, reference being had to the accompanying drawings, in which:

Figure 1 is a longitudinal sectional elevation of a complete structure embodying the subject of my invention, taken on the line I—I, Fig. 3.

Fig. 2 is a longitudinal sectional eleva-

tion of the rotating drum, taken on the line II—II, Fig. 3.

Fig. 3 is a cross sectional view on the line III—III, Fig. 1, showing the drum in the 60 closed, operative position.

Fig. 4 is a similar cross sectional view, showing one of the chambers of the drum discharging the contained material; one of the movable doors having been opened for 65 the purpose, and showing the sampling cover open.

Figs. 5 and 6 are sectional views on the line V—V, and VI—VI, Fig. 1, and

Figs. 7, 8, and 9 are views illustrating 70 structural details within the scope of my invention.

The rotating drum 1, forming the subject of my invention may be made up of a frame comprising an end wall 2, and longitudinal 75 elements 3, which latter members may be joined to an annular flange 4, of said end wall, and connected at their opposite ends to the annular flange of a head 5, having a tapering wall.

The external wall of the drum may be made up of a series of doors or covers 7, each of substantially the same character and connected to one of the longitudinal elements 3 by hinges 8. These doors or covers have their marginal edges grooved at 9, for the reception of gaskets 10, for contact with the frame of the drum, and clamping means are provided whereby said doors or covers may be held in liquid-tight engagement with 85 the contacting portions of the drum frame. Said clamping means may comprise L-shaped members 11 overlying the doors and fitting over bolts 12; being held down by handled nuts 13.

One of the doors or covers 7 may carry a supplemental door 15, secured and held in liquid-tight engagement thereto in the same manner that the doors 7 are secured to the frame, which door 15 normally closes an 100 opening 16, through which samples of the material under treatment can be removed from time to time to observe the action of the dye liquor, as indicated in Fig. 4.

The interior space of the drum is divided into a series of compartments or chambers 17, for the reception of the goods under treatment, by means of double-walled partition elements 20; each of said partition elements being made up of an inner imperforate wall 21, an outer imperforate wall 22, in engagement with one of the longitudinal

elements 3, and to which it may be secured, and foraminous walls 23, connecting the walls 21 and 22, preferably integrally; said walls 23 preferably paralleling each other and being spaced apart to provide chambers 24. The inner walls 21 of these partition elements form, with a series of foraminous partition plates 25, concentrically disposed with respect to the axis of rotation, a central chamber 26, into which the dye liquor may pass from the material receiving chambers 17, and from which it is withdrawn in the manner hereinafter described. The walls 21 may be flanged to partially overlie the foraminous plates 25 and be secured thereto.

Disposed a short distance from the imperforate inner walls 21 of these partition elements, I provide each of the latter with a foraminous wall 27, and in the spaces 28, thus provided, steam pipes 29, may be disposed. The chambers 24, formed between the walls of the partition elements are designed to receive initially the dye liquor forced into the rotating drum by means of a suitable pump 30, as indicated in Fig. 7; such liquor discharging from said partition chambers 24, into the material receiving chambers 17, and passing therefrom to the central chamber 26, for exit. Within the tapered head 5, of the drum, these partition members 20, may be connected together by a shell 31, in the form of a truncated cone, fitting within said head, and secured thereto in any suitable manner, and the spaces between the partition elements may be closed by walls 32.

Disposed beyond the head 4, is a shell-like structure comprising a pair of chambers 35 and 36 concentrically disposed, the outer wall of the structure forming the chamber 35 fitting within the bell mouth 37, of the tapered head 5, which bell mouth additionally receives packing material 39, held in place by a gland 40, suitably arranged to take up the packing and insure a liquid-tight joint between said bell end and the shell of the chamber 35. The shell of the inner chamber may fit within a central extension 41, of the end shell of the partition element; the meeting faces of the respective members being such as to permit rotation of one with respect to the other. Although the shell of such inner chamber is shown as fitting within the extension 41, it will be understood that the relation of the parts may be reversed without departing from my invention. To insure a liquid seal at such point, the contacting faces may be annularly grooved at 42 and 43, respectively; such grooves preferably registering and adapted to receive any liquor which may seep between the faces, and such liquor collecting in such registering grooves will prevent passage of the liquor past the joint.

The outer concentric chamber of the fixed casing extends beyond the inner chamber to a throat 45, which may be connected to a suitable pump 30, as indicated in Fig. 9, whereby dye liquor, gas or any other fluid may be introduced into the drum, and such liquor discharging from said concentric chamber, enters the shell 31; passing thence to the chambers 24 of the partition elements 20, and is discharged therefrom through the foraminous walls 23, into the material receiving chambers 17, of the drum, from which it passes through the foraminous plates 25, to the central chamber 26, and then discharges into the inner chamber 36, of the fixed shell for re-circulation by the pump, or complete discharge from the drum, as may be desired.

At the opposite end of the drum, the end plate 2, may be connected to a casting 46, receiving at one end a steam pipe 47, with a suitable packed joint; a gland 48, being provided for the purpose, and such member 46, may be bored to provide a series of passages 49. The inner end of these passages 49, adjacent the end plate 2, receives the steam pipes 29, disposed within the spaces 28, of the partition elements 20. The steam pipes 29 are perforated throughout their length so that steam may be discharged therefrom and find its way into the chambers 24, of the partition members 20, to heat the body of dye liquor, the arrangement indicated serving to equalize the temperature of the dye liquor.

The member 46, may carry a cone 50, between which and a second cone 51, carried by a support 52, anti-friction balls 53, may be placed, to provide a suitable bearing. The tapered head 5, at the opposite end of the drum may also be provided with a cone 55, between which and an outer cone 56, carried by a support 57, anti-friction balls 58 are disposed.

By providing the head 5, with a suitable pulley face, as indicated at 60, the drum may be rotated by a suitable belt from a driven element, or, in lieu of the pulley face, the tapered head may carry a gear wheel 61, so as to be positively driven by a motor driven pinion, or from any other suitable form of prime mover.

One or all of the chambers 17, of the drum may be provided with a drain valve 62, near the outer margin of the drum so that one of said valves will be lowermost when the drum is in any one of the discharging positions; and the end wall 2, may also carry one or a series of liquid gage glasses 63, which may be disposed opposite the partition elements in order that the height of the dye liquor within the drum may be ascertained at any time.

While I have described my improved apparatus as being specially designed and em-

ployed for dyeing, preferably employed for dyeing material in bulk, it will be understood that it may be employed for the treatment of various materials, and for the operations of scouring and bleaching; and that in lieu of introducing dye liquor into the chambers containing the material operated upon, I may introduce gaseous bodies, bleaching fluids, securing liquids and the like, without departing from my invention.

While I have described a form of apparatus in which the liquor is first discharged to the chambers of the partition element 20, located in the peripheral portion of the interior of the drum and returned through a central passage or chamber, it will be understood that the liquor may be introduced centrally and discharged via the hollow partition elements without departing from my invention.

I claim:

1. In apparatus for dyeing or otherwise treating fibrous material, the combination of a cylindrical shell forming a liquid-containing drum, a series of foraminous partitions or walls radially disposed and dividing the interior of said drum into a series of longitudinal chambers, means for rotating the drum, and means for introducing dye liquor into one end of the chambers formed by said foraminous partition elements for free circulation through the chambers of said drum:

2. In apparatus for dyeing or otherwise treating fibrous material, the combination of a shell forming a liquid-containing drum, a series of foraminous partitions or walls radially disposed in pairs within said shell, foraminous walls disposed longitudinally of the drum between the inner ends of said partition elements to form a central chamber; said walls and partition elements dividing the interior of the drum into a series of chambers some of which are peripherally disposed, and means for freely circulating dye liquor throughout the chambers of said drum.

3. In apparatus for dyeing or otherwise treating fibrous material, the combination of a rotatable shell forming a liquid-containing drum, a series of foraminous-walled compartments extending longitudinally of said drum out of contact with each other, a series of foraminous plates disposed longitudinally of the drum in engagement with the inner ends of said foraminous-walled compartments whereby a central chamber is formed at the axial portion of the drum space, and means for passing treating liquid into and through said foraminous-walled compartments for free circulation throughout the chambers between the same and out through said central chamber.

4. In apparatus for dyeing or otherwise treating fibrous material, the combination of

a rotatable shell forming a liquid-containing drum, hollow trunnions at opposite ends of said drum adapted to receive fluid, a series of double-walled foraminous partitions disposed within said drum and dividing the interior of the same into a series of goods-receiving chambers, means for rotating the drum, and means for introducing dye liquor through the trunnion at one end of said structure into the double-walled foraminous partitions for free circulation through said drum.

5. In apparatus for dyeing or otherwise treating fibrous material, the combination of a rotatable shell forming a liquid-containing drum, hollow trunnions at opposite ends of said drum adapted to receive fluid, a series of double-walled foraminous partition elements dividing the interior of said drum into a series of chambers, a central chamber having foraminous walls affording communication with the chambers between the partition elements, means for rotating the drum, means for introducing treating fluid through one of said trunnions for passage to one end of the double-walled partition elements and means for introducing steam through the other trunnion for passage to said foraminous partition elements.

6. In apparatus for dyeing or otherwise treating fibrous material, the combination of a drum, a series of foraminous partitions disposed longitudinally of said drum, a concentric foraminous shell axially disposed; said axial shell and foraminous partitions dividing the interior of the drum into a series of chambers, some of which are peripherally disposed and adapted to receive goods to be treated, movable doors or covers closing the wall of the drum opposite said peripheral chambers and in fluid-tight engagement with the drum; one of said doors having a supplemental sampling opening, and a fluid-tight door for closing said sampling opening.

7. In apparatus for dyeing or otherwise treating fibrous material, the combination of a rotatable shell forming a liquid-receiving drum, hollow trunnions at each end of said drum adapted to serve as fluid conduits, double-walled foraminous partition elements each having a plurality of chambers in communication with each other; said partition elements dividing the interior of the drum into a series of chambers, means for rotating the drum, means for introducing dye liquor at one end of said double-walled partition elements for circulation through the chambers of the drum, and perforated pipes in communication with one of said trunnions and disposed within one of the chambers of said double-walled partition elements for the introduction of steam to heat the circulating liquid.

8. In apparatus for dyeing or otherwise

- treating fibrous material, the combination of a shell having openings in its wall, covers hinged thereto and normally closing said openings in the shell to form a liquid-receiving drum, a series of partition elements radially disposed within said drum and in contact with the peripheral wall of the same; said partition elements comprising pairs of foraminous walls enclosing longitudinal chambers and dividing the interior of the drum into a series of longitudinal goods-receiving chambers to which access may be gained by opening said covers, means for rotating the drum, and means for introducing dye liquor into one end of said double-walled partition elements for free circulation throughout the chambers of the drum.
9. In apparatus for dyeing or otherwise treating fibrous material, the combination of a drum comprising an imperforate cylindrical shell, a series of double-walled foraminous partition elements radially disposed and in contact with the peripheral wall of the drum; said partition elements dividing the interior of the drum into a series of chambers and said drum having openings communicating with said chambers, covers hinged to said shell and normally closing said openings, foraminous plates disposed between the inner ends of said partition elements and forming a central chamber, means for rotating the drum, and means for circulating dye liquor into and through said foraminous partition elements and the chambers between the same and out through the central chamber of the drum.
10. In apparatus for dyeing or otherwise treating fibrous material, the combination of a drum comprising a shell having a truncated conical head, a series of partition elements connected to a second shell disposed within said head and fitting radially within the drum; said partition elements having foraminous walls disposed in pairs to form longitudinal chambers peripherally disposed, an axial chamber, foraminous walls dividing the same from the peripheral chambers, means at one end of the drum for introducing treating fluid for free circulation therein, and means at the opposite end of the drum for introducing steam into the partition elements; the latter having spaces to receive steam pipes.
11. In apparatus for dyeing or otherwise treating fibrous material, the combination of a liquid-containing drum comprising a shell having a truncated conical head, a second shell comprising a series of radially disposed double-walled partition elements and a truncated conical head continuous with said partition elements fitting concentrically within the first named shell; each of said partition elements having foraminous walls and enclosing a pair of chambers; a series of foraminous walls disposed between the inner end of the radially disposed partition elements and forming a central chamber, means for introducing treating fluid at one end of the partition elements for free circulation throughout the drum, means at the opposite end of the structure for introducing steam into the said partition elements, and steam distributing pipes connected thereto and disposed within said partition elements.
12. In apparatus for dyeing or otherwise treating fibrous material, the combination of a drum comprising a shell having a truncated conical head, a series of double-walled foraminous partition elements connected to a shell within said head and fitting radially within the drum, an axial chamber, foraminous walls dividing the same from the peripheral chambers, means at one end of the drum for introducing dye liquor for circulation therein, means at the opposite end of the drum of introducing steam into the partition elements; the latter having spaces to receive steam pipes, and hollow trunnions upon which the drum is adapted to rotate and through which the fluid bodies may pass to the interior of the drum.
13. In apparatus for dyeing or otherwise treating fibrous material, the combination of an imperforate shell forming a liquid-containing drum, a series of double-walled foraminous partition elements radially mounted therein, a central foraminous shell connected to said partition elements; said central shell and radial partition elements dividing the interior of the drum into a series of chambers, movable doors for closing openings in the wall of the shell opposite the chambers between the radial partition elements, and means for securing said doors in fluid-tight engagement with the shell.
14. In apparatus for dyeing or otherwise treating fibrous material, the combination of a shell forming a fluid-containing drum, a plurality of double-walled foraminous partition elements dividing said drum into a series of chambers; each of said partition elements having a plurality of chambers in radial alignment, means for rotating the drum, and means for introducing treating fluid into said partition elements for circulation throughout the chambers of said drum.
15. In apparatus for dyeing or otherwise treating fibrous material, the combination of a rotatable shell forming a liquid-containing drum, hollow trunnions at opposite ends of said drum adapted to form conduits for the passage of fluid to said drum, a plurality of double-walled foraminous partition elements radially disposed and dividing said drum into a series of chambers, means for rotating the drum, and means for circulat-

ing treating liquid through said drum; one of said trunnions having a plurality of passages.

16. In apparatus for dyeing or otherwise treating fibrous material, the combination of a liquid-containing drum comprising a shell having a tapered head, covers hinged to said shell, a series of double-walled foraminous partition elements radially disposed in contact with the periphery of the drum, and dividing the interior of the latter into a series of chambers; the latter having openings closed by said covers, a tapered head continuous with said partition elements and fitting within the tapered end of the shell, means for rotating the shell, and means for circulating treating liquid throughout the chambers within the same.

17. In apparatus for dyeing or otherwise treating fibrous material, the combination of a liquid-containing drum comprising a shell having a truncated conical head, a shell comprising a series of radially disposed double-walled partition elements and a truncated conical head continuous with said double-walled partition elements fitting within the drum; the side walls of said partition elements being perforated throughout their entire extent, foraminous partition elements connected to said radial partition elements to form an axial chamber, means at one end of the structure for introducing treating fluid to the ends of said partition elements for circulation throughout the chambers of the shell; said liquid being discharged through the axial chamber, means for rotating said shell, and a trunnion having concentric passages for inlet and discharge of the treating liquid.

40 18. In apparatus for dyeing or otherwise treating fibrous material, the combination of a drum comprising a frame having a truncated conical head, a series of double-walled foraminous partition elements having a head at one end fitting within the conical head of the drum, foraminous walls associated

with the partition elements and forming an axial chamber, means at one end of the drum for introducing treating fluid for circulation therein, means at the opposite end of the drum for introducing steam into the partition elements, and hollow trunnions upon which the drum is adapted to rotate and through which the fluid bodies may pass to the interior of the drum. 50

19. In apparatus for dyeing or otherwise treating fibrous material, the combination of a shell forming a liquid-containing drum, hollow trunnions at each end of said drum, a series of double-walled foraminous partition elements radially disposed within said drum, and means for rotating said drum, one of said trunnions having concentric passages, the inner passage being in communication with the central portion of the drum 60 and the outer passage being in communication with the double-walled partition elements. 65

20. In apparatus for dyeing or otherwise treating fibrous material, the combination of a rotatable shell forming a liquid-containing drum, a series of foraminous compartments extending longitudinally of said drum out of contact with each other and having flanged inner ends, a series of foraminous plates in engagement with the inner flanged ends of said foraminous compartments whereby a central chamber is formed at the axial portion of the drum space longitudinally thereof, means for passing treating fluid through said foraminous compartments for free circulation in the chambers between the same, hollow trunnions for said drum; one of said trunnions having a passage in communication with the foraminous compartments and a passage communicating with the central chamber, and means for rotating said drum. 70 75 80 85

In witness whereof I have signed this specification.

HOWARD M. DUDLEY.
